AIRCRAFT ANTENNA GUY FITTING

William C. Rogers, Miami Springs, Fla. (P.O. Box 48-205, International Airport Branch, Miami, Fla.)

Original design application Apr. 26, 1961, Ser. No. 64,905. Divided and this application Apr. 9, 1964, Ser. No. 79,660

Term of patent 14 years

(Cl. D54—11)

FIGURE 1 is a perspective view illustrating the wire receiving end and one side of an aircraft antenna guy fitting embodying my new design;

FIGURE 2 is a side elevational view thereof; and

FIGURE 3 is an elevational view of the wire receiving end thereof.

The dominant features of the design reside in the portions shown in full lines in the drawings.

This application is a division of my co-pending application, Serial Number D. 64,905, filed April 26, 1961.

I claim:

The ornamental design for an aircraft antenna guy fitting, substantially as shown and described.
